US00D930136S

(12) **United States Design Patent** (10) **Patent No.:** **US D930,136 S**
(45) **Date of Patent:** **** Sep. 7, 2021**

(54) **FILTER ELEMENT**

- (71) Applicant: **Cummins Filtration IP, Inc.**,
Columbus, IN (US)
- (72) Inventors: **Jessie A. Knight**, Oregon, WI (US);
Scott G. Manke, Sun Prairie, WI (US)
- (73) Assignee: **CUMMINS FILTRATION IP, INC.**,
Columbus, IN (US)
- (**) Term: **15 Years**
- (21) Appl. No.: **29/733,863**
- (22) Filed: **May 7, 2020**

Related U.S. Application Data

- (62) Division of application No. 29/646,936, filed on May 8, 2018, now Pat. No. Des. 884,866.
- (51) **LOC (13) Cl.** **23-04**
- (52) **U.S. Cl.**
USPC **D23/365**

(57) **CLAIM**

We claim the ornamental design for a filter element, as shown and described.

DESCRIPTION

FIG. 1 is a bottom perspective view of the claimed design, according to a first embodiment;
FIG. 2 is a top perspective view thereof;
FIG. 3 is a bottom plan view thereof;
FIG. 4 is a top plan view thereof;
FIG. 5 is a front elevation view thereof;
FIG. 6 is a rear elevation view thereof;
FIG. 7 is a left side elevation view thereof;
FIG. 8 is a right side elevation view thereof;
FIG. 9 is a bottom perspective view of the claimed design, according to a second embodiment;
FIG. 10 is a top perspective view thereof;
FIG. 11 is a bottom plan view thereof;
FIG. 12 is a top plan view thereof;
FIG. 13 is a front elevation view thereof;
FIG. 14 is a rear elevation view thereof;
FIG. 15 is a left side elevation view thereof; and,
FIG. 16 is a right side elevation view thereof.
The broken lines formed by dashes show unclaimed subject matter and form no part of the claimed design.

1 Claim, 14 Drawing Sheets
